(57) **CLAIM**

The ornamental design for a cover for a snowboard or a skateboard, as shown and described.

DESCRIPTION

FIG. 1 is a perspective view of a cover for a snowboard or skateboard showing my new design;
FIG. 2 is a front view thereof;
FIG. 3 is a back view thereof;
FIG. 4 is a side view thereof; and,
FIG. 5 is a top view, the view from the rear side being identical.
